(57) **CLAIM**

The ornamental design for a fiber optic transceiver, as shown and described.

DESCRIPTION

FIG. 1 is a front top perspective view of a fiber optic transceiver showing our new design;

FIG. 2 is a rear top perspective view thereof;

FIG. 3 is a front bottom perspective view thereof;

FIG. 4 is a front elevational view thereof;

FIG. 5 is a rear elevational view thereof;

FIG. 6 is a left side elevational view thereof, the opposite side view being a mirror image;

FIG. 7 is a top plan view thereof; and

FIG. 8 is a bottom plan view thereof; and,

FIG. 9 is a perspective view of the transceiver shown mounted on a board and engaged by a corresponding plug, which are shown in broken lines for illustrative purposes only and form no part of the claimed design.
